CHARLES E. GODLEY, OF DETROIT, MICHIGAN, ASSIGNOR TO EDMUNDS & JONES CORPORATION, OF DETROIT, MICHIGAN, A CORPORATION OF NEW YORK.

FOCUSING DEVICE

1,426,857.

Specification of Letters Patent. Patented Aug. 22, 1922.

Application filed December 15, 1920. Serial No. 430,958.

To all whom it may concern:

Be it known that I, CHARLES E. GODLEY, a citizen of the United States, and residing at Detroit, in the county of Wayne and 5 State of Michigan, have invented a new and Improved Focusing Device, of which the following is a specification.

This invention relates to electric head-lights and spotlights for motor vehicles, 10 search lights for motor boats and in general to lamps provided with projectors, and its object is to provide means for so mounting the light bulbs relative to the reflectors that the incandescent points of the bulbs 15 may be brought to the focal points of the reflectors by moving these incandescent points both longitudinally of the focal axis of the reflector and transversely thereto.

Few of the incandescent light bulbs for 20 automobile head lamps are correct or uniform in construction for most of them have the light points of their filaments at one side of the central lines. No particular standard seems to be followed for the distance of the light point from the end of 25 the base for the bulb. It is necessary therefore that means be provided for so supporting the light bulbs that they can be moved both longitudinally of the axis of 30 the reflector and transversely thereto to obtain good results.

The invention shown in the accompanying drawing and set forth in the following claims is adapted to accomplish this purpose.

In the accompanying drawing, Fig. 1 is a central longitudinal section of a head-light provided with my improved focusing device. Fig. 2 is a similar section of the 40 focusing device for a headlight having a flattened rear end. Fig. 3 is an elevation of a fastening clip. Fig. 4 is an elevation of a collar.

In Fig. 1 the cup shaped lamp body 1 has 45 a spherical central portion 2 provided with a central aperture 3 to receive the internally threaded hub 4 on the bearing plate 5. This plate may have its edge turned out to constitute a flange 6 so that it may be firmly 50 grasped to slide the plate around. Within the body 1 is a reflector 7 having a central aperture 13 and the center of the spherical portion 2 of the body is preferably in the middle of this central aperture in the reflector.

A connector sleeve 8 is formed with

threads 9 which fit the internally threaded hub 4 and which sleeve may be turned in this hub by means of the connector plug 10 and its pins 11 which extend into the bayonet slots 12 in this sleeve in the usual manner. A light bulb 14 has a base 15 provided with pins 16 which enter the usual slots 17 in this sleeve. This construction is clearly shown in detail by the Knauff patent number 1,059,617, dated April 22, 1913, although any other type of connector for either single or double contact bulbs and plugs may be employed if desired. A collar 19 having a spherical face bears against the interior of 60 the spherical portion 2 of the body 1 under pressure of the spring 20, and together with the plate 5, hold the focusing device in position. A second and mainly flat collar 18 is 65 slidable on this sleeve being limited by the clip 22 which straddles the sleeve 8 and is seated in the circumferential groove 21 therein. The collar 18 has a notch 31 to receive the rearwardly extending finger 23 on this clip and thus holds the clip in its 70 groove. The clip cannot be removed until the collar 18 has been moved back sufficiently to free this pin.

As stated before, the incandescent point 25 of the filament of the light bulb 14 is not 85 always in the central line of the base of the bulb. In order to bring the incandescent point into the axis of the reflector, the plate 5 is moved around on the spherical portion 2 of the lamp body to move the incandescent 90 point to the axis of the reflector and the connector sleeve 8 is turned in or out to move the incandescent point to the focus of the reflector. As the center of curvature of the part 2 of the body is at the center of the 95 opening 13 in the reflector, this opening need be but little greater than the diameter of the connector tube 8.

To remove the parts, the light bulb and reflector are taken out of the body 1 and the 100 collar 18 is pressed back against the spring until the finger 23 on the clip 22 is released, when the clip may be slipped up out of its groove. The collars 18 and 19 and the spring 20 between them may now be slipped 105 off the sleeve 8 and this sleeve and the plate 5 taken out together through the opening 3.

In the construction shown in Fig. 2, the sleeve 8 has the threads 9 and the slots 12 and 17 to receive the pins 11 on the connector plug 10 and the pins 16 on the base 15 of the light bulb. It also has a circumfer-

ential groove 21 to receive the clip 22 whose into the body through the aperture, said finger 23 extends into a notch 31 in the collar 18 and is thereby held in its groove. The central portion 2^a of the lamp body is flat 5 and against it bear the flat bearing plate 5^a and the flat washer 19^a. The opening 3^a in the central portion 2^a of the lamp body permits lateral movement of the hub 4 in any direction and the opening 27 in the reflector 10 is of sufficient size to permit this movement. The spring 20 is again of sufficient stiffness to so firmly press the collar 19^a against the interior of the body as to prevent any displacement of the connector except under 15 considerable pressure on the flange 6^a. In this case again, the sleeve and the light bulb may be moved longitudinally of the axis of the reflector and transversely thereto to bring the incandescent portion of the filament 20 of the bulb into the focus of the reflector to produce a concentrated beam of light or to move it away from such focal point in order to obtain a diffused illumination. In the second case the sleeve 8 will 25 always be parallel to the axis of the reflector while in the first case, the central line of the sleeve will always be a radius of the spherical part 2 of the reflector. In the first case, the disk 5 must be moved in a direction 30 opposite to that desired for the filament, while in the second case the plate 5^a is moved in the same direction.

The details and proportions of the various parts of this focusing device may all be 35 changed by those skilled in the art without departing from the spirit of my invention as set forth in the following claims.

I claim:

1. In a headlight, the combination of a body having an aperture, a connector sleeve extending into the body through said aperture, and means attached to said sleeve and gripping the metal of the body around the aperture to hold the sleeve in desired position, the diameter of the aperture being sufficient to permit lateral movement of the sleeve therein, said gripping means comprising a plate fitting against the body around the aperture and attached to the sleeve, a 45 collar movable longitudinally of the sleeve and means including a spring to force the collar and plate toward each other with the metal of the body between them.
2. In a headlight, the combination of a body having an aperture, a connector sleeve extending into the body through said aperture, a light bulb mounted in said sleeve and means attached to said sleeve and gripping the metal of the body around the aperture to hold the sleeve in desired position, the diameter of the aperture being sufficient to permit lateral movement of the sleeve therein, said gripping means comprising a 55 plate fitting against the outside of the body and an internally threaded hub extending
3. In a headlight, the combination of a body having an aperture, a connector sleeve extending into the body through said aperture, a light bulb mounted in said sleeve and means attached to said sleeve and gripping the metal of the body around the aperture to hold the sleeve in desired position, the diameter of the aperture being sufficient to permit lateral movement of the sleeve therein, said gripping means comprising a 60 plate fitting against the outside of the body and an internally threaded hub extending
4. In a headlight, the combination of a cup-shaped body and a reflector therein, both having apertures central with the axis of the reflector, a connector sleeve extending through the apertures, a lamp bulb mounted in the inner end of said sleeve, a plate on the outside of the body and attached to the sleeve, a collar on the inside of the body slidable relative to the sleeve, a second collar on the sleeve forward of the first, a spring between said collars to press the slidable collar toward the plate to grip the metal of the body between them, and means to prevent the forward collar from sliding forward, the apertures in the body and the reflector being sufficiently larger than the sleeve to permit lateral movement thereof.
5. In a headlight, the combination of a cup-shaped body and a reflector therein, both having apertures central with the axis of the reflector, a connector sleeve extending through the apertures, a plate on the outside of the body and attached to the sleeve, a collar on the inside of the body movable longitudinally of the sleeve, a second collar on the sleeve forward of the first, a spring between said collars to press the slidable collar toward the plate to grip the metal of the body between them, and means to prevent the forward collar from sliding forward, the apertures in the body and the reflector being sufficiently larger than the sleeve to permit lateral movement thereof, said collar retaining means comprising a clip mounted in a circumferential groove in the sleeve and having a rearwardly extending finger, said forward collar having a notch to receive the pin to hold the clip in said groove.
6. In a headlight, the combination of a cup-shaped body and a reflector therein,

both having apertures central with the axis of the reflector, the body surrounding the aperture therein being flat and at substantially right angles to the axis of the reflector, a connector sleeve extending through said apertures, a flat plate fitting the outside of the flat end of the body and attached to said connector sleeve, a collar slidable longitudinally of said sleeve, and means in- cluding a spring to force the collar and 10 plate toward each other with the metal of the flat portion of the body between them to hold the sleeve in position, the diameter of the aperture in the body being sufficient to permit lateral movement of the sleeve 15 relative to the axis of the reflector.

CHAS. E. GODLEY.
